UNITED STATES PATENT OFFICE.

JOHN K. KOPCHUK, OF MELVILLE, SASKATCHEWAN, CANADA.

GRAIN-DOOR.

1,400,080.

Specification of Letters Patent. Patented Dec. 13, 1921.

Application filed August 19, 1920. Serial No. 404,517.

To all whom it may concern:

Be it known that I, JOHN K. KOPCHUK, a citizen of Ukraine, residing at Melville, in the Province of Saskatchewan and Dominion of Canada, have invented certain new and useful Improvements in Grain-Doors, of which the following is a specification.

This invention relates to certain new and useful improvements in grain doors.

10 The primary object of the present invention resides in the provision of a door especially designed for grain car bins or the like wherein the door is formed of a plurality of sliding shutter sections and moving from opposite sides of a door opening toward the center thereof to provide a complete closure for the opening.

15 A further object of the invention is to provide a grain door formed of a plurality of shutter sections slidably associated with each other and divided on a horizontal line to provide independently operable upper and lower sections.

20 A still further object of the invention includes the provision of locking arms associated with the shutter door sections to prevent the sections from being opened when the locking arms are in their operative positions.

25 With the above general objects in view and others that will appear as the nature of the invention is better understood, the same consists in the novel form, combination and arrangement of parts hereinafter more fully 30 described, shown in the accompanying drawings and claimed.

In the drawings, wherein like reference characters indicate corresponding parts throughout the several views,

35 Fig. 1 is a front elevational view of a door and frame therefor constructed in accordance with the present invention, one of the upper door sections being moved to its open position,

40 Fig. 2 is a horizontal sectional view taken on line II-II of Fig. 1 showing the sliding door panels moved to their closed position relative to the door opening with the locking arms in their positions,

45 Fig. 3 is a vertical sectional view taken on line III-III of Fig. 1,

50 Fig. 4 is a vertical sectional view similar to Fig. 3 with the door sections removed and the locking arms in their folded inoperative positions,

55 Fig. 5 is a detail sectional view taken on

line V-V of Fig. 6, showing two of the door panel sections slid to their extended positions,

Fig. 6 is a front elevational view of a pair 60 of panel sections, with one of said panels partially broken away, and

Figs. 7 and 8 are perspective views of the lower and upper door panels, respectively.

Referring more in detail to the accompanying drawings, and particularly to Figs. 1 and 2 there is illustrated a frame structure 1 representing a car side silo wall or bin, having a door opening therein defining a sill 2 and an upper rail 3 with the side 70 walls thereof constructed in channel formation to provide vertical side pockets 4 having entrance openings 5 in the inner walls 6 thereof.

The door construction embodies a plurality of panels slidably mounted upon each other as illustrated in Figs. 1 and 2 for housing within the pockets 4 when the same are moved to their open position, the panels being divided upon a horizontal line to provide lower sections 7 and upper sections 8,

20 two of the upper panel sections 8 being shown in detail in Figs. 5 and 6, the lower and upper panels 7 and 8 having recesses 9 formed in one face thereof and covered by 85 plates 10 that are slotted as at 11 for purposes presently to appear. The outer faces of the panels 7 and 8 are provided with the recesses 9 and slotted plates 10 and the panels are assembled in sliding relation similar 90

to a camera shutter, the rear face of one panel slidably engaging the front face of the adjacent panel while headed pins 12 as shown in Fig. 5 are carried by the rear face of each panel and extend into the panel 95

recesses 9 through the plate openings 11, thus locking the adjacent lower panels 7 and the adjacent upper panels 8 in sliding engagement with each other. The engagement between the upper and lower panels 8 and 7 100

includes the provision of a cutaway portion 13 upon the upper edge of each lower panel 7 and the provision of a depending plate 14 upon the lower end of each panel 8 with the plate riding in the cutaway portion 13 105

as clearly shown in Figs. 1 and 3. The upper and lower forward end panels 8' and 7' are fixed to the forward wall of the pocket 4 and the panels when in their extended position are arranged at an angle relative 110 to the transverse axis of the door opening while the outwardly extending panels 7 and

8 at one side of the door are provided with keeper hooks 15 and 16 respectively for engaging the opposite door panel sections to retain the doors in their closed position as shown in Figs. 1 and 2.

10 A locking device for retaining the door panels closed as illustrated in Figs. 1 and 2 embodies a pair of locking arms 17 hingedly mounted at their lower ends as at 18 upon the inner walls of the pockets 4 as shown in Fig. 4, the arms 17 having hinge extensions 19 with hooks 20 at the free ends thereof for engagement with each other when the arms are moved to their locking 15 position as shown in Fig. 2. A pair of arms 17 is mounted within each housing 4 adjacent the upper and lower ends thereof for securing the lower and upper closed panel sections 7 and 8 in their locked position. 20 The forward edges of the arms 17 and extensions 19 are inclined as at 21 and substantially contact the panel sections over the entire lengths thereof so that sliding movement of the panel sections will be prevented 25 when the locking arms are in the horizontal position shown in Fig. 2.

To open the door from the position shown in Fig. 2 the engaging ends 20 of the arm extensions 19 are free to permit the extensions to fold upon their hinge connections with the arms 17, after which the arms are moved within the housing 4 upon their hinged ends 18, whereupon the panel hooks 15 and 16 are released to permit the panel 30 sections to slide upon each other and be guided by the pin and slot connections 12 and 11 to enter the opening 5 in the pocket 4 and provide an unrestricted passage 35 through the door opening. With this construction of door, the opening therefor may be regulated by shifting any of the door sections, as by opening one of the upper sections as shown in Fig. 1 or either of the lower sections without disturbing the remaining 40 structure. An advantage is present in the fact that the locking device for the door panels is fastened to the door frame and when the door is in its open position the locking devices are hidden from view which 45 will prevent tampering with the same. 50

While there is herein shown and described the preferred embodiment of the present invention, it is nevertheless to be understood that minor changes may be made therein 55 without departing from the spirit and scope of the invention as claimed.

What is claimed as new is:—

1. A grain door of the type described comprising in combination with a door 60 opening having frame pockets at opposite sides thereof, a door formed of sliding panels adapted to extend across the door opening when in closed position and to be received in said pockets when in open position, and means adapted to be moved into

the path of opening movement of the panels to hold the same in closed position.

2. A grain door of the type described comprising in combination with a door opening having frame pockets at opposite 70 sides thereof, a door formed of sliding panels adapted to extend across the door opening when in closed position and to be received in said pockets when in open position, and locking means for the door panels 75 when in closed position, said means being mounted within the pockets.

3. A grain door of the type described comprising in combination with a door opening having frame pockets at opposite 80 sides thereof, a door formed of sliding panels adapted to extend across the door opening when in closed position and to be received in said pockets when in open position, and locking means for the door panels 85 when in closed position, said means being mounted within the pockets and positioned rearwardly of the door panels when the door is moved to its open position.

4. A grain door of the type described 90 comprising in combination with a door opening having frame pockets at opposite sides thereof, a sectional door formed of panels slidably mounted upon each other, pin and slot connections between adjacent 95 panels, locking arms pivotally mounted within the frame pockets and having inclined side edges adjacent the door panels with said edges lying in proximity of the door panels when the door sections are 100 moved to their closed position.

5. A grain door of the type described comprising in combination with a door opening having frame pockets at opposite 105 sides thereof, a sectional door formed of panels slidably mounted upon each other, pin and slot connections between adjacent panels, locking arms pivotally mounted within the frame pockets and having inclined side edges adjacent the door panels 110 with said edges lying in proximity of the door panels when the door sections are moved to their closed position, said locking arms being arranged in opposed relation, and connections between the arms when in 115 their locking position.

6. A grain door of the type described comprising in combination with a door opening, a sectional door formed of panels slidably mounted upon each other, and means hingedly carried by the side walls of the door opening and adapted to be moved into the path of opening movement of the doors to hold the same in closed position.

7. A grain door of the type described comprising in combination with a door opening, a sectional door formed of panels slidably mounted upon each other, and means hingedly carried by the side walls 125 130

of the door opening and adapted to be moved into the path of opening movement of the doors to hold the same in closed position, said means including pivoted arm sections adapted to be moved into the path of opening movement of the doors to hold the same in closed position.

8. A grain door of the type described comprising in combination with a door opening, a sectional door formed of panels slidably mounted upon each other, and means hingedly carried by the side walls of the door opening and adapted to be moved into the path of opening movement of the doors to hold the same in closed position, said means including pivoted arm sections adapted to be swung to a horizontal position and having outer edges in the path

of opening movement of the doors to hold the same in closed position.

20

9. A grain door of the type described comprising in combination with a door opening, a sectional door formed of panels slidably mounted upon each other, and means hingedly carried by the side walls of the door opening and adapted to be moved into the path of opening movement of the doors to hold the same in closed position, said means including pivoted arm sections adapted to be swung to a horizontal position and having outer inclined edges in the path of opening movement of the doors to hold the same in closed position.

25

In testimony whereof I affix my signature.

JOHN K. KOPCHUK.
